CLAIM

The ornamental design for a turret and magnification adjusting ring for a rifle scope, as shown and described.

DESCRIPTION

FIG. 1 is a perspective view a turret and magnification adjusting ring for a rifle scope, showing my new design;

FIG. 2 is a perspective view thereof;

FIG. 3 is a first side elevational view thereof;

FIG. 4 is a second side elevational view thereof;

FIG. 5 is front elevational view thereof, the view as shown is taken from the direction and viewpoint indicated at location 5—5;

FIG. 6 is rear elevational view thereof, the view as shown is taken from the direction and viewpoint indicated at location 6—6;

FIG. 7 is a top elevational view thereof; and,

FIG. 8 is bottom elevational view thereof.

The broken lines depict portions of the turret and magnification adjusting ring for rifle scope that form no part of the claimed design. The broken line showing of FIG. 1 is only partially depicted in the FIGS. 2 through 8 views.
